TABLE LAMP OR SIMILAR ARTICLE

Samuel J. Koch, Great Neck, N.Y., assignor to Soss Manufacturing Company, Detroit, Mich., a corporation of Nevada

Filed Apr. 22, 1965, Ser. No. 84,906

Term of patent 14 years

(Cl. D48—20)

FIG. 1 is a perspective view of a table lamp or similar article, showing my new design.

FIG. 2 is a side view thereof.

FIG. 3 is a top view thereof.

FIG. 4 is a front view thereof.

FIG. 5 is a rear view thereof.

The dominant features of my new design are shown in solid lines in the drawings.

The portions disclosed in broken lines are omitted in FIGS. 2 through 5 for the convenience of illustration.

I claim:

The ornamental design for a table lamp or similar article, substantially as shown and described.
